UNITED STATES PATENT OFFICE

HENRY COWAN, OF NEW YORK, N. Y.

DESIGN FOR A RUG OR SIMILAR ARTICLE

Application filed August 21, 1930. Serial No. 36,726. Term of patent 3½ years.

To all whom it may concern:

Be it known that I, HENRY COWAN, a citizen of the United States, residing at New York City, county of New York and State of New York, have invented a new, original and ornamental Design for a Rug or Similar Article, of which the following is a specification, reference being had to the accompanying drawing, forming part thereof.

I claim:

The ornamental design for a rug or similar article as shown.

HENRY COWAN.
